SHUFFLEBOARD WEIGHT

Paul Kotler, Irvington, N. J.

Application November 22, 1946, Serial No. 711,709

3 Claims. (Cl. 273—128)

1

It is among the objects of my invention to provide a shuffleboard weight which will be resistant to leaping and overturning, that will display the identity of the caster in a prominent manner so that his weight can be distinguished at a distance, that is relatively free from frictional drag, that imparts a direct impulse to other weights upon collision, that is relatively resistant to cracking and breakage, that has a low center of gravity, that provides a display area of the greatest possible extent without weakening or unbalancing the weight, and that is simple and inexpensive in construction.

These objects and advantages as well as many other objects and advantages will appear from a consideration of the accompanying drawings in which:

Figure 1 is a side elevation of my shuffleboard weight;

Figure 2 is a top view of my shuffleboard weight;

Figure 3 is a cross section of my shuffleboard weight taken on the line 3—3 in Figure 2; and

Figure 4 is a view of a modified shuffleboard weight.

My shuffleboard weight provides a disc shaped body member 11. The body member has convex sides 12. The apex of convexity 13 is located at a point which is equidistant from the bottom 14 and top 15 of the body member 11. The bottom 14 is very slightly conical with the apex of the cone 16 at the exact center of the bottom 14.

A depression 17 is formed in the center of the top 15. While the extent of the depression may be varied, it is preferred that it extend nearly one-half of the height of the body member 11. Immediately below the top 15, an annular internal groove 18 is located. The lower part of this groove supplies an abutment or a seat 19. The upper part of the groove is an overhanging lip 20. The lower part of the depression 17 contains a support 27 which extends to the level of the seat 19. A display member 21 is positioned on the seat 19. For protection of printed matter, a transparent disc 22 may be placed over the display member 21. The display member 21 may have advertising matter indicated thereon or may be colored or otherwise marked to make the weight readily identifiable and distinguishable by the person who has cast it. The disc 22 may be associated with the display member 21 by cement 23, or in any other suitable manner, or it may be left free. The display member 21 and the disc 22 are preferably "snap-fitted" into the annular groove 18.

The depression 17 serves to substantially lower the center of gravity of the body member 11 wherein it becomes more stable and resists the tendency to leap or overturn when it strikes another weight.

The location of the apex of convexity 13 at a

5 point equidistant from the top 14 and bottom 15 tends to insure a squarely dealt blow tangentially to other weights struck; this likewise tends to prevent overriding by the striking weight and provides direct impulsion to the struck weight without engendering leaping or overturning impetus.

10 The slightly conical base 14 reduces the area of the surface that rides on the shuffleboard. Friction is thereby minimized and the weight rides more freely. In addition, the smaller the surface that bears on the shuffleboard, the less wax that there is scraped off the board.

15 The location of the display member 21 at the top of the body member 11 makes the weight identifiable at a considerable distance.

Another form of my invention is illustrated in Figure 4. This weight is most readily identifiable at a distance because the display member 24 is convex. The transparent disc 25 is also convex. In order to supply proper support for the convex display member 24, the support member 26 is piano-convex.

20 The body member 11 is preferably formed of steel so that it may have the requisite heaviness in spite of the weight lost by the cut-out section forming the depressed central portion 17. By reason of the depression 17, the center of gravity is low. In order that the center of gravity be not substantially raised, the support members 26, 27 are preferably made of some light material such as cork or balsa wood, etc. The display members 21, 24 are preferably formed of plastic material. The transparent discs 22, 25 may likewise be formed of a transparent plastic material.

25 My improved shuffleboard weight, by reason of its convex sides, medial contact point, and low center of gravity provides an implement which does not override or overturn. By reason of its conical base, it is fast and free in movement. By reason of its display surface, which may be either flat or convex, it is readily distinguishable from the adversary's weight. By reason of the contact point 13 being relatively distant from the 30 lip 20, it is less subject to breakage. Not only is my weight a useful adjunct to shuffleboard, but it may, with only slight modification be used in many other games where a discoid weight is required.

35 The foregoing description is intended to be illustrative of preferred embodiments of my invention. Many changes may be made in the selection, arrangement and construction of the parts within the scope of the appended claims without departing from the spirit of my invention.

I claim:

40 1. A weight for a shuffleboard or the like comprising a discoid body member having a convex side with the apex of convexity at a point equidistant from the bottom and the top of the

body member, a conical bottom, a top, a depression in the top; an annular groove in the depression, an abutment defining a seat and a retaining lip in the depression; a display member positioned on the seat under the lip, and a support member under the display member.

2. A weight for a shuffleboard or the like comprising a discoid body member having a convex side, with the apex of convexity at a point equidistant from the bottom and the top of the body member, a conical bottom, a top, a depression in the top, an annular groove in the depression defining a seat, a display member positioned on the seat, and a support member under the display member.

3. A weight for a shuffleboard or the like comprising a discoid body member having a convex side with the apex of convexity at a point equidistant from the bottom and top of the body member, a conical bottom, a top, a depression in the top, an annular groove in the depression defining a seat and a display member positioned on the seat.
